UNITED STATES PATENT OFFICE.

ALOYSIUS J. COLEMAN, OF CHICAGO, ILLINOIS.

TOOTHBRAHSH.

Application filed September 13, 1923. Serial No. 662,437.

To all whom it may concern:

Be it known that I, ALOYSIUS J. COLEMAN, a citizen of the United States, and a resident of the city of Chicago, in the county of Cook 5 and State of Illinois, have invented certain new and useful Improvements in Tooth-brushes, of which the following is a specification.

This invention relates to improvements in tooth brushes, in which hair bristles have heretofore been set to fill an elongated solid head, provided with a rigid handle extending lengthwise thereof, and also to tooth brushes having the above described form, 15 heretofore provided with rubber bristles, which, together with a head therefor, are molded from resilient vulcanized rubber, the head being imperforate and provided longitudinally with a socket for sleeving it upon 20 and securing it to a stiff handle of any suitable material.

Hair bristle tooth brushes of any structural form commonly in use, are subject to a number of objections, among which may 25 be mentioned the difficulty of their manipulation without painful contact of the brush head and the bristles with the corners of the lips and the very sensitive inner tissues of the mouth adjacent the teeth and gums, 30 when removing food from the exposed surfaces of the teeth and gums, and the impossibility of extracting food deeply seated between the teeth, without seriously painfully irritating and not infrequently lacer- 35 ating the gums from being scratched and penetrated by the ends of the bristles; that such tooth brushes provide a convenient receptacle and a fertile bed for the rapid propagation of the bacilli of disease germs 40 from any source, and especially bacilli resulting from the decomposition of food between the teeth, and not only spread their poison in the gums, but distribute it to other parts of the mouth, throat and body; and 45 that, at best, hair bristle tooth brushes are not sanitary and but few of the many using them attempt to so make or keep them.

On the other hand, rubber bristle tooth brushes, owing to the necessary resilience 50 of their bristles, are not adapted for removing, in its entirety, food deeply seated between the teeth, but do furnish a successful means for removing food deposits from the exposed inner and outer surfaces of the 55 gums and teeth, for polishing the latter, and

the best possible means for thoroughly massaging the gums, without painful contact of the brush head and bristles with the lips and the very sensitive inner tissues of the mouth adjacent the teeth and gums.

Medical and dental authorities agree that many ailments of the body generally, pyorrhea, decay of the teeth, especially at the roots, and also tonsilitis and ulcerations of the mouth, are directly attributable to decomposition of food lodged between the teeth, producing bacilli which are transmitted to and poisonously infect the gums and other parts of the mouth and body; that irritated and lacerated gums and other parts of the mouth and throat retain, fertilize and promote the growth and spreading of such bacilli; that the thorough cleansing of the mouth, teeth and gums of food deposits therein will prevent the occurrence 75 of any and all of such diseases; and, finally, that existing diseases of the gums are curable and that the gums may be healed and hardened by thoroughly cleansing them of all food deposits, concurrently with the application of an antiseptic and massaging them sufficiently to reach into their crevices and expel pus and congested blood therefrom, without irritating or lacerating the gums, as will be readily understood by bearing in mind that pyorrhea starts with tender, spongy, bleeding gums, followed by 80 their receding.

From the foregoing, it will now be apparent that a tooth brush, the material, construction and form of which are such that it is adapted for cleansing the teeth of all food deposits, applying an antiseptic directly to infected gums, insuring the destruction of bacilli in the gums and throughout the mouth, and massaging the gums sufficiently to maintain, and, if diseased, restore them to a healthy condition, without irritation and laceration, and which is easily operated and comparatively cheap of construction, will be a substantial and material improvement in the art.

The object of my invention broadly stated, therefore, is a tooth brush, the material, form and construction of which are cheap, 105 convenient and easy of manipulation, for quickly removing from and cleansing the teeth of food deposits, as far as may be, by brushes of other forms and materials, for injecting a cleansing liquid, and, when dis-

eased, an antiseptic solution directly between the teeth and gums with a force sufficient to insure the removal of any food deposits remaining therein, following the 5 brushing operation, and for massaging the gums and polishing the teeth, in the absence of any liability to objectionably irritate or lacerate the gums.

More specifically stated, the object of my 10 invention is a tooth brush, the brush head and bristles of which are integrally formed of a frictional material, non-irritating to the gums and interior tissues of the mouth, provided with a detachable handle, and with 15 means for supplying and forcibly ejecting from the brush head, between the bristles, a liquid solution cleansing the teeth of food deposits.

A further object of my invention is to 20 provide a hollow head tooth brush with a detachably connected nozzle through which to forcibly supply a liquid to said head by means of a compressible bulb, which nozzle is flat and thereby adapted to inject a flat 25 sheet of water directly between the teeth for promoting and perfecting the cleansing of the same of food deposits.

Another object of my invention is a tooth brush, including a hollow perforated brush 30 head and bristles formed of resilient vulcanized rubber, a hollow handle therefor, a rubber bulb, provided with a flattened nozzle, which brush head, handle and nozzle are frictionally respectively detachably connected, one with the other.

With these ends in view, my invention finds embodiment in certain features of novelty in the construction, combination and arrangement of parts by which the said 40 objects and certain other objects are attained, all as hereinafter fully described with reference to the accompanying drawings and more fully pointed out in the claims.

In said drawings, 45 Fig. 1 illustrates, in vertical, longitudinal section, a tooth brush in which my invention finds embodiment.

Fig. 2 is a horizontal view of said brush, partly in horizontal section.

50 Fig. 3 is a transverse section taken on line 3—3 of Fig. 1.

Fig. 4 is a transverse section taken on the line 4—4 of Fig. 1; and

55 Fig. 5 is a front elevation of the brush head and bristles detached from the handle.

Similar characters of reference indicate the same parts in the several figures of the drawing.

The brush head 6 of my invention preferably 60 consists of resilient vulcanized rubber and with suitable rubber bristles 7, integrally connected therewith, the brush head being molded hollow to provide a longitudinal chamber 8 closed at its forward end 65 with a series of open perforations 9 for the

discharge of liquid outwardly from the brush head between the bristles, there being a sufficient number of perforations for the cleansing of the bristles and for supplying a liquid for cleansing the teeth, as far as 70 may be, by a rubber bristle tooth brush.

The brush head 6 is frictionally secured to a handle 10, the forward end of which projects preferably to contact with the closed end of the brush head and is provided with a cut-away portion 11 in open communication with the perforations 9 for the free and unobstructed discharge through the perforations of liquid forcibly supplied through the handle, preferably formed from hard 80 rubber, but may be of other suitable material.

Removably projecting into and frictionally tight in the open end of the handle is a 85 wedge-shaped nozzle 12, the stem 13 for which is reduced, as indicated at 14, to form a seat for a rubber bulb 15, sleeved frictionally tight on the stem, but removable therefrom.

In the construction of the nozzle portion, the discharge passage therefor is preferably smaller than the passage in the nozzle stem, and, likewise, the passage in the body of the handle is larger than the discharge passage therefor surrounded by the brush head, for the purpose of producing and directing small jets of water from the brush head to impact with the teeth and gums and particularly between the teeth, both back and front, continuously and with the greatest 90 possible compressible force consistent with the operation of the bulb.

The purpose in utilizing friction for connecting the brush head with the handle, and the nozzle with the handle and the bulb, 95 is to provide a simple and convenient means for the cleansing and renewal of these several parts and packing them within the smallest possible compass for shipment, and particularly by parcel post.

For cleansing healthful teeth and gums, the nozzle is first disconnected from the stem and the bulb filled with a cleansing liquid, or else, if desired, with a tooth paste or other tooth-cleansing solution, this being followed by introducing the nozzle to its operative position in the handle, and during the brushing of the teeth compressing the bulb from time to time for directing outwardly through the bristles, jets of water, under a force sufficient to cleanse the teeth of food loosened by the bristles, and the bristles and the brush head from particles of food otherwise clinging to the bristles and brush head.

When disease is present in the gums or teeth or any part of the mouth or throat, the bulb should be filled with a pronounced antiseptic solution, for not only sterilizing the diseased tissues and teeth, but any and all germs of disease possibly deposited from 125 130

any source, and otherwise retained by the bristles and brush head.

For using the tooth brush before described, containing my invention, with the several parts in their operative position, as shown in Figs. 1 and 2, the nozzle is first removed from the handle, and, after being filled with a cleansing liquid, a pronounced antiseptic or other solution, as may be desired or necessary, it is reinserted in the handle, followed by reciprocating the brush to contact with the teeth, as may be, at any angle, and with any force of impact necessary for scraping food deposits from the exposed inside and outside surfaces of the teeth, and for loosening and digging out, as far as may be, deep deposits of food between the teeth concurrently with the compression of the bulb and the forcible ejection of liquid from the brush head outwardly between the teeth.

For actuating the brush, the operator grasps the stem of the nozzle between his thumb and forefinger, compressing the bulb between his remaining finger and the palm of his hand, and continues the brushing and massaging operation until all food so deposited is removed and carried away by the liquid.

If, however, there is any reason to believe that any food may possibly remain between the teeth or imbedded in the gums next the teeth, the bulb with its nozzle is removed from the handle and, if empty, again filled, followed by projecting the flat nozzle vertically between the teeth and forcing liquid therethrough until such food deposits are removed therefrom.

It may be that in some instances it is desirable to so employ the nozzle before the brushing action, but this is not ordinarily the case, for the reason that a sufficient scraping and digging force of the bristles may be applied to the teeth and gums to cleanse them and effectively massage the gums without the possibility of irritating or lacerating them.

In conclusion, it is now to be observed that the concept of my invention is a tooth brush, the bristles of which are adapted for scraping and digging food deposits from the teeth and gums, and massaging the gums, in the absence of any possibility of lacerating or injuriously irritating the tissues of the gums and mouth, which brush is provided with means for directing between and beyond the bristles a number of liquid jets to impact against and between the teeth with a force sufficient to eject

food deposits therefrom, and with a bulb having a flat nozzle detachably connected with a hollow brush head.

Having described my invention, what I claim and desire to secure by Letters Patent is:

1. A tooth brush structure comprising a hollow brush head having ducts establishing communication between the bristles and the interior of said head and one end open for the reception of a handle, a tubular handle having one end slidably received within said head, the free end of said handle being provided with a socket, and a compressible bulb having a rigid nozzle frictionally and detachably secured in the handle socket.

2. A tooth brush comprising a hollow brush head having ducts establishing communication between the interior thereof and the bristles, a tubular handle having one end removably received in said head, the free end of said handle being formed into a polygonal, tapered socket, a rigid nozzle having flat faces frictionally secured within the handle socket, and a compressible bulb connected to said nozzle.

3. A tooth brush construction comprising a brush head hollowed to provide a liquid receiving chamber throughout the major portion of its length, ducts being provided to establish fluid communication between said chamber and the bristles, and one end of said head being open for the insertion of a handle, a tubular handle having one end flattened and slidably received in the brush head and terminating next the end wall of the chamber, said flattened end being provided with an elongated discharge outlet within the chamber, a nozzle detachably received in the free end of said handle, and a compressible bulb communicating with said nozzle.

4. A tooth brush construction comprising a bristle carrying head provided with a chamber in the head in open communication with the bristles, said head and bristles being formed wholly of resilient vulcanized rubber, a handle detachably socketed in and terminating adjacent one end of said brush head chamber, provided with a longitudinal passage in open communication with said chamber, and a compressible bulb and a flat nozzle therefor removably socketed in said handle.

In witness whereof, I have hereunto set my hand this 25th day of September, 1923.

ALOYSIUS J. COLEMAN.
